SKIRT OR SIMILAR ARTICLE

Samuel Feldman, Forest Hills, N. Y., assignor to Knit Wear Patents, Inc., Atlanta, Ga., a corporation of Georgia

Application September 20, 1952, Serial No. 21,536

Term of patent 14 years

(Cl. D3—26)

To all whom it may concern:

Be it known that I, Samuel Feldman, residing at Forest Hills, in the county of Queens, State of New York, have invented a new, original, and ornamental Design for a Skirt or Similar Article, of which the following is a specification, reference being had to the accompanying drawing, forming part thereof.

Fig. 1 is a front perspective view of a skirt or similar article, showing my new design.

Fig. 2 is an enlarged view of a portion of the skirt shown in Fig. 1, showing the details of construction of the horizontal band which interrupts the vertical ribs.

The back of the skirt has the same appearance as the front thereof.

I claim:

The ornamental design for a skirt or similar article, as shown and described.

SAMUEL FELDMAN.
